US00D914717S

(12) United States Design Patent (10) Patent No.: US D914,717 S
Mensinger et al. (45) Date of Patent: * Mar. 30, 2021

(54) DISPLAY SCREEN OR PORTION THEREOF WITH GRAPHICAL USER INTERFACE

(71) Applicant: DexCom, Inc., San Diego, CA (US)

(72) Inventors: Michael Robert Mensinger, San Diego, CA (US); Eric Cohen, San Diego, CA (US); Phil Mayou, San Diego, CA (US); Eli Reihman, San Diego, CA (US); Katherine Yerre Koehler, San Diego, CA (US); Rian Draeger, San Diego, CA (US); Angela Marie Traven, San Marcos, CA (US)

(73) Assignee: DexCom, Inc., San Diego, CA (US)

() Term: 15 Years

(21) Appl. No.: 29/593,698

(22) Filed: Feb. 10, 2017

Related U.S. Application Data

(63) Continuation of application No. 29/495,688, filed on Jul. 2, 2014, now Pat. No. Des. 778,929, which is a continuation-in-part of application No. 13/842,679, filed on Mar. 15, 2013, now Pat. No. 9,801,541.

(57) CLAIM

The ornamental design for display screen or portion thereof with graphical user interface, substantially as shown and described.

DESCRIPTION

FIG. 1 shows a front view of a display screen or portion thereof with graphical user interface that incorporates the new, original, and ornamental design; and, FIG. 2 shows another embodiment thereof.

The broken lines illustrate the display screen or portion thereof with graphical user interface and form no part of the claimed design.

1 Claim, 2 Drawing Sheets
